UNITED STATES PATENT OFFICE.

ALFRED W. JANSEN, OF BROOKLYN, NEW YORK.

DESIGN FOR A WASHSTAND.

50,272.

Specification for Design.

Patented Feb. 6, 1917.

Application filed June 3, 1916. Serial No. 101,621. Term of patent 7 years.

To all whom it may concern:

Be it known that I, ALFRED W. JANSEN, a citizen of the United States, residing at Brooklyn, in the county of Kings and State of New York, have invented a new, original, and ornamental Design for a Washstand, of which the following is a specification, reference being had to the accompanying drawing, forming part thereof.

The figure is a perspective view of a wash stand showing my new design.

I claim:—

The ornamental design for a washstand as shown.

ALFRED W. JANSEN.
